[57] **CLAIM**

The ornamental design for a housing for an electrical connector, as shown and described.

DESCRIPTION

FIG. 1 is a perspective view of a housing for an electrical connector showing my new design;

FIG. 2 is a front elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a rear elevational view thereof;

FIG. 8 is a cross-sectional view thereof taken along line 8—8 of FIG. 2;

FIG. 9 is a cross-sectional view thereof taken along line 9—9 of FIG. 2;

FIG. 10 is a cross-sectional view thereof taken along line 10—10 of FIG. 4.
